ATTORNEYS.

UNITED STATES PATENT OFFICE.

JACOB TUNICK, OF BROOKLYN, NEW YORK.

SPOON.

Application filed August 16, 1928. Serial No. 299,948.

This invention is a spoon so constructed that it is adapted to serve as a container in which substances may be vended in sealed condition and which spoon is capable of being unsealed by the ultimate purchaser who is thereupon adapted to employ the spoon in the usual manner.

The invention is susceptible of employment in the arts generally, but is particularly intended to be used by druggists in dispensing medical powders. Under the present practice of dispensing medical powders a predetermined quantity of the powder is measured with the ingredients mixed therein in proper proportions and the whole quantity is then subdivided into a number of smaller quantities which are individually packaged in small sections of paper. These papers are individually folded by the druggist about the subdivided portions of the powder and are, after folding, packed in boxes of a dozen or more powders as the physician may prescribe. This well known practice of packaging powders is a slow and tiresome method of dispensing such substances, and the primary object of the present invention is, therefore, to provide a simple and efficient construction for packaging powders in a more economical and expeditious manner.

In its preferred practical embodiment, the invention is in the form of a spoon which, in practice, may conveniently be in the form of a cardboard or papier-mâché stamping or may be formed in molds or in any other way desired. The bowl of the spoon constitutes the container in which the powder or other substance is adapted to be received. The free edge of the bowl is shaped to provide a stepped seat while the handle of the spoon is provided at its free end with a disk shaped to cooperate with this stepped seat, and preferably slightly offset with the remainder of the handle so that if the handle is folded at a point midway of its ends, the disk may be moved into cooperative relation with the seat and snapped in place so as to cover the open side of the bowl and form a manually removable closure therefor. The natural resiliency of the material from which the spoon is formed will normally hold the disk in sealing position, so that it cannot inadvertently become displaced.

With an arrangement of this character, it will be apparent that it is only necessary to deposit the powder or other substance in the bowl and then bend the handle of the spoon

so as to introduce the disk into cooperative relation with the seat whereupon the packing of the substance is completed. The time consuming methods heretofore employed in the packaging of powders are thus entirely obviated by this invention which may be manufactured at such nominal cost as to render packaging of powders more economical with the present invention than under prior practice.

Features of the invention, other than those adverted to, will be apparent from the hereinafter detailed description and claims, when read in conjunction with the accompanying drawing.

The accompanying drawing shows one practical embodiment of the invention, but the construction therein shown is to be understood as illustrative, only, and not as defining the limits of the invention.

Figure 1 is a plan view of a spoon embodying the present invention with the parts in unfolded condition.

Figure 2 is a section perspective on the line 2—2 of Figure 1.

Figure 3 is a longitudinal section through the spoon with the handle folded to effect sealing of the contents of the bowl.

Referring to the drawings, 1 designates the bowl of the spoon, and 2 the handle thereof. Both the bowl and handle may be of any appropriate shape or contour, but, for the purpose of illustration, I have shown the bowl as substantially semispherical. The bowl is provided at its open free edge with a stepped seat 3, so that the margin of the bowl is in the form of an upstanding flange 4. The handle 2 is provided at its free end with a disk 5, which may be cupped if desired but is shown as flat. This disk is slightly offset where it joins the handle as shown at 6 so that when the handle is bent midway of its length as indicated at 7, the disk 5 can be snapped into cooperative relation with the seat 3, the flange 4 and disk 5 having sufficient inherent resiliency to retain the disk in position against inadvertent displacement as indicated in Figure 3.

In order to render the handle more rigid, it may be longitudinally corrugated as shown at 8, so that when the parts are folded, they will appear as shown in the last mentioned figure.

The packaging of powder or other substances in the bowl of the spoon while employing the extension of the handle to serve

as a sealing closure therefor is highly efficient for its intended purposes and may be accomplished with ease and expedition. When it is desired to unseal the bowl, this 5 may be readily accomplished by flexing the handle, say, for example, in the direction indicated by the arrow 9 in Fig. 3. The forcing of the handle in this direction, while the bowl of the spoon is held stationary will cause 10 the disk 5 to be snapped out of its seat and the handle may thereupon be straightened out into the condition shown in Fig. 2 to permit the spoon to be used in the usual manner. That is to say, the contents of the spoon 15 may be taken directly into the mouth or such contents may be deposited in a tumbler of water and stirred by the spoon. The spoon of this invention may be constructed from any suitable material, but stiff paper, cardboard or papier-mâché have been found efficient and economical.

While I have described the invention as particularly adapted by use by druggists, I do not limit its use for this specific purpose 25 as it may be used in other fields without departing from the invention, the scope of which is to be understood as fully commensurate with the appended claims.

Having thus fully described the invention, 30 what I claim as new and desire to secure by Letters Patent is:

1. A spoon, the bowl of which is provided at its open side with a marginal recessed seat and the handle of which spoon is provided at 35 its free end with a closure of a size and shape to cooperate with said seat whereby the handle of the spoon may be bent midway of its length to permit cooperation between the

closure and the seat for the purpose of sealing the confines of the bowl.

2. A spoon, the bowl of which is provided at its open side with an interior seat and the handle of the spoon having an extension at its free end of a size and shape to cooperate with said seat and form a closure for the bowl 45 of the spoon whereby the handle may be bent intermediate its ends to bring the enlarged extension of the handle into cooperative relation with the seat to seal the confines of the bowl.

3. A spoon, the bowl of which is provided at its open side with a marginal recessed seat and the handle of which spoon is provided at its free end with a closure of a size and shape to cooperate with said seat whereby the handle of the spoon may be bent midway of its length to permit cooperation between the closure and the seat for the purpose of sealing the confines of the bowl, said handle being longitudinally corrugated to enhance 60 its rigidity when the construction is employed as a spoon.

4. A spoon, the bowl of which is provided around its open top with a recessed seat and the handle of which spoon is provided at its free end with a stepped up closure disk of a shape and size to cooperate with the seat whereby the handle may be bent intermediate its ends to permit the closure disk to be brought into engagement with the seat of 70 the bowl to form a sealed closure within the bowl of the spoon.

In testimony whereof I have signed the foregoing specification.

JACOB TUNICK.
